UNITED STATES PATENT OFFICE.

EDWARD T. BURGESS, OF CORNING, NEW YORK.

DESIGN FOR GLASSWARE.

SPECIFICATION forming part of Design No. 13,041, dated July 18, 1882.

Application filed May 13, 1882. Term of patent 7 years.

To all whom it may concern:

Be it known that I, EDWARD T. BURGESS, of the village of Corning, in the county of Steuben and State of New York, have invented a new and original Design to be Cut into or upon Glassware; and I do hereby declare that the following is a full and clear description of the same, reference being had to the annexed drawing, (Patent Office No. 61,196,) which makes a part of this description and specification.

This design is a combination of stars, octagons, or hobnails and diamonds formed by series of parallel miter cuts into the surface of

any glassware. The miter cuts or grooves are 15 represented in the annexed drawing by the lines A A and B B, cut at the respective angles of 26° and 64° and forming the figures as shown.

I claim--

The miter cuts or grooves A A and B B at the angles and in the relative positions and forming the figures and faces as shown.

EDWARD T. BURGESS.
